UNITED STATES PATENT OFFICE.

WILSON E. PORTER, OF NEW HAVEN, CONNECTICUT, ASSIGNOR TO THE
NEW HAVEN CLOCK COMPANY, OF SAME PLACE.

WATCH.

SPECIFICATION forming part of Letters Patent No. 540,874, dated June 11, 1895.

Application filed May 31, 1894. Serial No. 512,969. (No model.)

To all whom it may concern:

Be it known that I, WILSON E. PORTER, of New Haven, in the county of New Haven and State of Connecticut, have invented a new Improvement in Stem-Winding and Stem-Setting Watches; and I do hereby declare the following, when taken in connection with the accompanying drawings and the letters of reference marked thereon, to be a full, clear, and exact description of the same, and which said drawings constitute part of this specification, and represent, in—

Figure 1, a view, partly in section and partly in elevation, of a watch constructed in accordance with my invention and looking toward its upper movement-plate and showing its winding-train; Fig. 2, a corresponding but less comprehensive reverse view of the watch, looking toward its lower movement-plate and showing its setting-train; Fig. 3, a view of the watch in vertical central section on the line *a b* of Fig. 1, showing it adjusted for winding; Fig. 3^a, a similar view showing the watch adjusted for setting; Fig. 4, a detached broken plan view showing the bearing-plate and the manner of mounting it in the upper and lower movement-plates of the watch, together with the intermediate winding and setting wheels; Fig. 5, a detached view in side elevation showing the winding and setting arbor, the winding and setting wheels, and the bearing-plate; Fig. 6, a detached plan view of the setting-wheel; Fig. 7, a view corresponding to Fig. 5, but showing a modification of the means employed for coupling the winding and setting arbor with the winding-wheel; Fig. 8, a plan view of the winding-wheel shown by Fig. 7; Fig. 9, a view in side elevation showing a modified mode of coupling the winding and setting arbor with the setting-wheel.

My invention relates to an improvement in stem-winding and stem-setting watches, the object being to produce a simple, effective and reliable winding and setting mechanism, composed of few parts, durable in use, and not liable to derangement.

With these ends in view, my invention consists in a stem-winding and stem-setting mechanism having certain details of construction, as will be hereinafter described, and pointed out in the claims.

In carrying out my invention, I employ a winding-wheel A, and a setting-wheel B, respectively located upon opposite sides of a bearing-plate C, which is mounted in the upper edges of the front and back movement-plates D and D' of the watch, in a plane at a right angle to the said plates, which are suitably notched to receive it. The said wheels A and B are constructed with central openings to receive a longitudinally movable and rotatable winding and setting arbor E, which passes through them, and also through an opening *c*, formed in the said bearing-plate. The outer end of the said arbor is screwed into a circular socketed head F, formed at the inner end of the stem F', the outer end of which is threaded, and screwed into the crown G, which is fitted over the outer end of the pendant H, the inner end of which is secured to the watch-case I, and the outer end of which carries the ring H'. A spiral spring J, located in a chamber H' formed in the pendant, presses against the head F, and the opposite end of the chamber H', and exerts a constant effort to force the said arbor inward, and maintain it in its normal or winding position, from which it is moved into its setting position by pulling outward upon the crown against the force of the said spring. The said arbor E is alternately coupled with the winding-wheel A, and the setting wheel B, and its and their adaptation to that end is susceptible of wide variation. As shown in Figs. 1, 2, 3 and 5 of the drawings, the said arbor is constructed with a circular ratchet K, located about midway of its length, and having its teeth adapted to take into the teeth of a circular hub A', formed upon the upper face of the winding-wheel A. At its extreme inner end the arbor is furnished with a transverse coupling pin L, the projecting ends of which are received in slots B', leading out of the central opening of the setting-wheel B, and arranged in pairs opposite each other, the aligned slots of one pair standing at a right angle to those of the other pair as shown by Fig. 6. When the arbor is in its normal position in which it is held by the spiral spring J, the ratchet K is engaged with the toothed hub A', whereby the arbor is coupled with the winding wheel so as to rotate the same in case the crown is turned for-

95 100

ward, while on the other hand, if the crown is turned backward, the circular rack K will "ratchet back" as the term is, over the toothed hub A'. The watch is normally therefore in 5 readiness for winding. At this time the arbor being projected inward, the coupling pin L is maintained in a position beyond the plane of the inner face of the setting-wheel. When it is desired, however, to set the watch, the crown 10 is engaged by the fingers, and drawn outward, bringing the arbor with it, with the effect of disconnecting the circular ratchet K from the hub A', and drawing the pin L into one pair of notches in the setting-wheel B, which will 15 now be connected with the arbor, and be rotated in either direction thereby, while the winding wheel will be disconnected therefrom. It will thus be seen that the arbor is connected with either the winding or the setting wheel according to its position.

The winding-wheel A is permanently in mesh with the intermediate winding-wheel M, which in turn is permanently meshed into the barrel wheel N, mounted on the barrel or 20 spring arbor N'. On the other hand the setting-wheel B is permanently meshed, as clearly shown in Fig. 2, into the intermediate setting-wheel O, which meshes into the minute wheel O', which carries an hour pinion O², 25 meshed into by the hour-wheel O³, mounted on the center-arbor O⁴, which also carries the minute pinion O⁵. The particular construction and arrangement of the winding and setting trains are, however, immaterial, and may 30 be varied as desired, so long as each of them is in permanent connection with the winding and setting-wheels A and B, located upon the opposite faces of the bearing plate C.

I may here remark that in prior constructions of stem-winding and stem-setting watches, the wheels employed to connect the stem winding and stem setting arbor with the winding and setting trains, have been thrown into and out of gear alternately, while 40 in my construction, those wheels are permanently intermeshed with the trains, but not permanently connected with the winding arbor with which they are connected alternately.

It is apparent that in carrying out my invention, changes from the construction herein described may be made. Thus, instead of employing the annular ratchet K, and the hub A' for coupling the winding and setting arbor with the winding-wheel, I may employ other 50 devices, which may or may not permit the reverse rotation of the winding arbor.

If desired, I may adopt the construction shown by Figs. 7 and 8 of the drawings, in which the winding arbor P is provided with 60 two coupling-pins p p', the projecting ends of which are arranged to take into slots formed in the winding-wheel P' and the setting-wheel P², according to the position of the arbor which passes through both wheels, and through a 65 bearing-plate P³, corresponding to the bearing plate C before described. The slotting of

the winding-wheel P' is shown in Fig. 8, while the slotting of the setting-wheel corresponds to the slotting of the setting-wheel shown by Fig. 6. In the construction shown by Fig. 9 70 of the drawings, the extreme inner end of the arbor Q is provided with a toothed head Q', arranged to engage with a toothed hub Q², located upon the inner face of the setting wheel Q³, the said toothed head and hub taking the place of the coupling-pin L and slots B' of the construction first described. 75

As shown in Figs. 1 and 2 of the drawings, I have illustrated a small spiral spring R for holding the winding-wheel down upon the upper face of the bearing-plate C, but this spring is not essential and may be dispensed with.

I particularly wish to call attention to the fact that in any embodiment of my invention 85 the adaptation of the arbor to be coupled with the winding and setting wheels respectively is separate and independent, and located upon opposite sides of the bearing plate between the wheels.

Other variations than those described may 90 obviously be made, and I would have it understood that I do not limit myself to the construction illustrated and set forth, but hold myself at liberty to make such changes as 95 fairly fall within the spirit and scope of my invention. I am aware, however, that it is old to alternately couple a rotatable and longitudinally movable arbor with wheels in connection with the winding and setting trains 100 of a watch, and I do not, therefore, claim that construction broadly.

Having fully described my invention, what I claim as new, and desire to secure by Letters Patent, is—

1. In a stem-winding and stem-setting watch, the combination with the winding and setting trains thereof, of winding and setting wheels permanently meshed into the said trains, located in line with each other, and each having a central opening, a winding and setting arbor passing through the said wheels, and adapted to be alternately coupled with them, and means for pushing in and pulling out the said arbor, and rotating it, the arbor 110 being adapted at separated points located adjacent to the outer faces of the said wheels for being coupled with them, substantially as described.

2. In a stem winding and stem setting watch, 115 the combination with the winding and setting trains thereof, of winding and setting wheels permanently meshed into the said trains thereof, and located in line with each other, and each having a central opening, and a bearing-plate located between the said wheels, which bear against its opposite faces, a winding and setting arbor passing through the said wheels, and longitudinally movable independently of them, and adapted at points on opposite sides 125 of said plate and adjacent to the outer faces 130 of the said wheels to be coupled with them.

for their rotation alternately and means for pushing in and pulling out the said arbor and rotating it, substantially as described.

3. In a stem - winding and stem - setting watch, the combination with the winding and setting trains thereof, of winding and setting wheels permanently meshed into the said trains, located in line with each other, and each having a central opening, a winding and setting arbor passing through the said wheels, and adapted adjacent to the outer faces thereof to be coupled with them alternately for their rotation with it, one adaptation of the arbor for being coupled with one of the wheels consisting in a circular rack which takes into the adjacent wheel which is adapted thereto, substantially as set forth.

4. In a stem - winding and stem - setting watch, the combination with the winding and

the setting trains thereof, of winding and setting wheels permanently meshed into said trains located in line with each other, and each having a central opening, and a winding and setting arbor passing through the said wheels and adapted at points adjacent to the outer faces thereof to be coupled with them alternately, one of the said wheels having coupling slots arranged to receive the ends of a coupling-pin carried by the said arbor and forming one of its said adaptations, substantially as described.

In testimony whereof I have signed this specification in the presence of two subscribing witnesses.

WILSON E. PORTER.
